UNITED STATES PATENT OFFICE.

WILLIAM McCALLUM, OF YONKERS, NEW YORK, ASSIGNOR TO JOSEPH WILD & CO., OF NEW YORK CITY.

DESIGN FOR A CARPET PATTERN.

Specification forming part of Design No. 5,550, dated February 20, 1872.

Specification describing a new and original Design for Carpet, invented by WILLIAM McCALLUM, of Yonkers, in the county of Westchester and State of New York.

The photographic illustration fully represents my new design.

This invention consists in a new design for a carpet, which contains two novel features, to wit, the central figures A and B.

The figure A contains an oval, a, in the middle, which is surrounded by a wreath, b, as shown, and is placed on a light field, d, of hexagonal form. The figure B is in shape of a fanciful shield, and is decorated by flowers and scrolls, as shown, and placed upon an hexagonal field, e.

The colors of the design may be varied at pleasure.

I claim as my invention—

1. The design of the figure A, as shown.
2. The design of the figure B, as shown.
3. The design for a carpet containing the figures A and B, as shown.

WILLIAM McCALLUM.
